DISPLAY BOX

John K. Darragh, New York, N. Y., assignor to
Florence A. Darragh

Application August 29, 1933, Serial No. 687,268

4 Claims. (Cl. 206—44)

This invention relates to slide boxes and more especially to slide boxes of carton size adapted to act as shipping containers for a plurality of rows of nested articles, such as cups or the like.

5 The especial object of this invention is to provide a slide box of this type which may act not only as a shipping container for the goods, but also as a display container for the sale of the same, and which at the same time shall be cheap and 10 economical in manufacture.

For a full understanding of the invention, there is shown in the accompanying drawing forming 15 a part of this specification, a construction embodying the invention, which will now be described in detail and the features forming the invention then specifically pointed out in the claims.

In the drawing:

Figure 1 is a side elevation in perspective, with 20 parts broken away, of the slide box in display position;

Figure 2 is a section on line 2—2 of Figure 1;

Figure 3 is a side elevation in perspective of the 25 slide box with the parts thereof in position for closing of the box, or as the case may be, for setting up in display position; and

Figure 4 is a side perspective of the closed slide box.

Referring to the drawing, a slide box, usually, 30 comprises a drawer, or tray A, having bottom, side, and end panels connected together with the top of the tray open, and a cover B having bottom, top, and side panels connected together, with one or both ends open to form a sleeve within which the drawer is housed, the drawer being 35 moved endwise through the sleeve cover for access to the drawer contents.

In accordance with the present invention, the 40 sleeve cover B is divided into a retaining band portion 1 and a support or easel portion 2 connected together across the bottom panel of the sleeve cover B by a line of scoring 3 forming a hinge for the band 1 and easel 2. The line of scoring 3 divides the bottom panel of sleeve cover B into two substantially equal parts and the opposite side panel cuts separating band 1 from 45 easel 2 may be of the reversed S curvature shown to provide an extension 4, the length of this extension being preferably such that its edge shall engage the bottom panel of the drawer A above the pivotal connection of the band 1 and easel 2 when in display position, as shown in Figures 1 and 2. The extension 4 operates therefore, not only as a support for the upper end of the drawer A, but also to prevent endwise separation of band 50 1 and easel 2 when in display position. The

outer ends of band 1 and easel 2 are preferably cut off at 5 on a suitable angle to provide a flat, even bearing with the supporting surface.

In setting the slide box, as shown in Figure 4, in display position, it is only necessary to move the drawer A outwardly through the band 1 end of the sleeve cover B, as shown in Figure 3, until the scoring 3 substantially coincides with the upper end of the drawer A, so that the easel portion 2 of the sleeve cover B may be swung freely about the end of the drawer A. The drawer A is then moved back through the band portion 1 of the sleeve cover B and the box is set up in display position as shown in Figure 2. To close the box, it is only necessary to reverse the above movements.

The upper, or easel end of drawer A may, with advantage, be formed to provide a pocket or shelf portion 6 by cutting the opposite side panels of the drawer A, as at 7, and connecting these 20 across the bottom panel by a line of scoring. The shelf portion 6, when the box is in display position, may be swung about the pivotal line of scoring and overlie the easel portion 2 of sleeve B, as shown in Figures 1 and 2, thus operating 25 as a convenient support for some of the box contents, if desired, and securing increased access to the box contents.

It will be seen that cutting off the sleeve ends at a suitable angle, as at 5, with the longer 30 sleeve panel operating as a closure for the open top of the drawer results in securing not only increased bearing surface and more rigid support for the box with ready finger hold for manipulation of the box elements, but also is 35 very advantageous in securing increased exposure of the box contents without loss of strength or stability while maintaining substantially the same band space for advertising matter.

It will be understood that the invention is not 40 limited to the specific construction shown and described as this may be modified within the invention as defined by the claims.

What I claim is:

1. A slide box having its sleeve cover formed 45 in two parts comprising an easel and a band hingedly connected, and its drawer formed in two parts hingedly connected to permit movement of a part of the drawer into a position overlying the easel when in display position. 50

2. A slide box having its cover formed in two 55 parts comprising an easel and a band hingedly connected and so arranged that the band surrounds the lower portion of the box drawer and the easel supports the upper end of the drawer 55

when in display position and a shelf forming a part of the box drawer and hingedly connected thereto to permit movement thereof into a position overlying the easel when in display position.

5 3. A slide box having its cover formed in two parts comprising an easel and a band hingedly connected, an extension on the easel cooperating with the box drawer above the hinge connection for support of the upper end of the drawer when in display position, and a shelf forming part of the box drawer and hinged thereon to turn back over the easel when in display position.

4. A display slide box having a box drawer, and a sleeve cover therefor formed in two parts comprising an easel and a band hingedly connected, the opposite ends of the sleeve cover being cut off at an angle, with the top panel of the sleeve cover longer than the bottom panel thereof, whereby a flat even bearing for the box is secured in the display position thereof with the upper edge of the lower end of the box drawer lying within and intermediate the ends of the sleeve 10 band. 6

JOHN K. DARRAGH.
